UNITED STATES PATENT OFFICE.

WILLIAM H. HUGHES, OF BIRMINGHAM, ALABAMA.

STEAM GRATE-SHAKER.

No. 845,090.

Specification of Letters Patent.

Patented Feb. 26, 1907.

Application filed January 18, 1905, Serial No. 241,682.

To all whom it may concern:

Be it known that I, WILLIAM H. HUGHES, a citizen of the United States, and a resident of Birmingham, in the county of Jefferson 5 and State of Alabama, have made certain new and useful Improvements in Steam Grate-Shakers, of which the following is a specification.

My invention is an improvement in apparatus for shaking pivoted grates or grate-sections. It is capable of general application in boiler and other furnaces, but is especially useful in locomotives for freeing the grates thereof of clinkers and other foreign substances mingled with the coal. By my invention coal which carries a high per cent. of ash can be utilized without undue clogging of the furnace-arch, and slack coal can be mainly consumed instead of passing through the flues in such quantity as to obstruct the net covering the smoke-box.

The details of construction, combination, and operation of parts are as hereinafter described, and shown in the accompanying drawings, in which—

Figure 1 is a face view of my improved apparatus applied to a locomotive fire-box. Fig. 1^a is a perspective view of a bearing for the rock or shaker shafts. Fig. 2 is a side view of the same. Fig. 3 is a horizontal section of one of the fluid-motor cylinders and its steam-chest, together with the connections between the piston-rod and the rock or shaker shaft. Fig. 4 is a transverse section of 35 the distributing-valve used in connection with each fluid-motor cylinder. Fig. 5 is an enlarged face view of a portion of one of the fluid-motor cylinders and its valve-chest, together with the hand-lever mechanism for 40 operating the distributing-valve arranged in 45 said valve-chest. Fig. 6 is a face view of the two fluid-motor cylinders, together with the steam-pipe connections for one of them and the mechanism connecting its piston with the adjacent shaker-shaft. Fig. 7 is a vertical section further illustrating the connection between one of the shaker-shafts and the grate proper and also means for locking such shaker-shaft.

50 The drawings illustrate my invention as applied to a locomotive-boiler and rocking grate therefor; but, as before indicated, I do not intend to thus limit its use.

In Fig. 1 the locomotive fire-box is shown 55 provided with a hinged door 1 and in Fig. 2

with rocking grate-sections 2 and a drop or dump grate-section 3, the latter being arranged contiguous to the end wall of the fire-box. It is to operate such grate-sections, or others of some analogous type, that my invention is applicable.

I arrange two vertical rock or shaker shafts 4 and 4^a on opposite sides of the aforesaid door 1, the same being journaled in fixed bearings 5 and 6, secured to the end of the fire-box. Each of these rock-shafts is provided at its lower end with a lateral arm 7, one of which is connected by a rod or link 8 (see Fig. 2) with devices depending from the movable grate-section 2, while the other arm 7 is connected by similar means (not shown) with a like grate-section. (Not shown.) In other words, while a single rock-shaft may be employed for shaking a grate, I prefer to employ two such shafts and to operate or rock them simultaneously for shaking separate grate-sections. For this purpose I employ the following mechanism, namely: two steam-cylinders 10 10^a, which are juxtaposed horizontally end to end and each provided 80 with a slideable piston 11, (see Fig. 3,) whose rod 12 is connected with a lateral arm 13, fixed on the upper end of each rock-shaft 75 4 and 4^a.

As shown in Fig. 6, each of the fluid-motor 85 cylinders is provided with trunnions 14, the same being arranged oppositely on the upper and lower sides of each cylinder. As shown at the left in Fig. 6, the trunnions are journaled in bearings 15, the same being extended laterally, as indicated in Fig. 1, and bolted to the head of the fire-box. Each cylinder is thus adapted to rock or oscillate as required to operate in connection with the lateral arms 13 of the rock-shaft 4. Each 95 cylinder 10 and 10^a is provided with a steam-chest 16, in which is arranged a distribution-valve 17, the same having a rod 18, (see Figs. 5 and 6,) which is pivoted to a vertical hand-lever 19, the same being pivoted at its lower end 20. This lever works in an arc-shaped keeper 21, which limits its throw in opposite directions. It is apparent that by vibrating said lever 19 the valve 17 will be reciprocated in the steam-chest, as required to govern 105 admission of steam to the cylinder through the ports 22, (see Fig. 3,) the steam being thus alternately admitted and exhausted from each side of the piston, whereby the latter is reciprocated and the rock-shafts 4 4^a 110

oscillated for imparting a rocking movement to the grate-sections 2, as will be readily understood. Steam is admitted to the steam-chests by pipes 23, (see Fig. 1,) which are suitably connected with the steam-dome of the boiler. These pipes in turn connect with the trunnions 14 of the respective motor-cylinders, the trunnions being hollow and suitable passages being provided in the walls of the cylinders for conducting steam to the opposite ends of the steam-chests, where it is introduced by openings 24. (See Fig. 3.) The valve 17 is hollow or provided with a central longitudinal passage, so that the valve is balanced, steam being always present in the spaces at both ends of the valve and under equal pressure therein and in the valve itself. The central portion of the valve is cut out or hollowed to allow space for exhaust, which is effected through the port 25. It will be seen that the steam-ports 22 and 25 are arranged in a well-known manner and that as the valve is shifted from one end to the other of the steam-chest 16 steam will be alternately admitted to and cut off from the respective ends of the adjacent motor-cylinder, while exhaust will take place correspondingly. Pipes 26 (see Fig. 1) are connected with the lower trunnions of the motor-cylinders for conducting the exhaust into the space beneath the grate or elsewhere, as may be preferred.

It will be seen that the valves 17 of the respective steam-chests may be vibrated or reciprocated by the hand-levers 19 whenever it is required to shake the grate-sections connected with the shaker-shafts 4 4^a, and it is further apparent that the two levers may be operated simultaneously or individually, as conditions may require, or, in other words, so that both portions of the grate with which the shaker-shafts are connected may be rocked together or separately.

As shown in Figs. 1, 2, and 7, a locking device consisting of a lever-arm 27 is pivoted to a lug on each of the rocking shafts 4 4^a, and is thus adapted to be placed in vertical position either up or down. When raised, as shown on the right-hand side of Fig. 1 and also in Fig. 2, the arm 27 is held or supported by a clevis-like keeper 28, the same being pivoted to the rock-shaft. On the other hand, when released from the keeper the said arm drops by gravity into the notch formed in the bearing or keeper 5, whereby the rock-shaft is locked or prevented from rotating on its axis, and thereby the grate-sections connected therewith are held steady in horizontal position. The lock is shown on the left in Fig. 1 and in Fig. 7. In case it is desired to shake the grate-sections manually a lever may be applied to the arms 27 and temporarily clamped thereto, as indicated by dotted lines in Fig. 7. Thus by vibrating 65 such lever laterally or in a horizontal direc-

tion a rock-shaft 4 or 4^a may be rotated with the corresponding result of oscillating the grate-sections.

The drop-section 3 of the grate may be lowered to vertical position, or, in other words, dropped, to allow dumping at that point by the following-described mechanism.

A sleeve 29 (see Figs. 1, 2, 7) is shown applied to the right-hand shaker-shaft 4^a, and it is provided at its lower end with a lateral arm 30, which is connected by a link or rod 31 with that end of the grate-section 3 which is farthest from the end of the fire-box. A lever 32 (see Figs. 1 and 2) is fixed on the upper end of the sleeve 29, and by moving the same horizontally in the proper direction—that is to say, outward or away from the end of the fire-box—the sleeve 29 will be rotated on the rock-shaft 4^a and the grate-section 3 thereby thrown down, as indicated in Fig. 2. When the lever is parallel to the face of the fire-box, as shown in Fig. 1, it may be held up by a keeper 33, or it may be allowed to hang vertical alongside the sleeve 29. Thus by comparatively simple means I am enabled to rock grate-sections by the admission of steam to the motor-cylinders or to dump portions thereof by the manipulation of the hand-lever.

What I claim is—

1. In a grate-shaking appliance, the combination of a shaker-shaft journaled in bearings on a fire-box and having upper and lower arms, a fluid-pressure-motor cylinder having a piston which is coupled to the upper arm of the shaker-shaft, a link by which the lower arm of said shaft is coupled to a plurality of rocking grate-bars, a pivoted drop-grate, a sleeve fitted freely on the shaker-shaft and coupled to the drop-grate, and a hand-lever coupled to said sleeve for raising and lowering the drop-grate by movement of the sleeve.

2. In a grate-shaking appliance, the combination of a shaker-shaft journaled vertically in bearings on the back head of a fire-box, upper and lower arms fixed on said shaft, a supporting-plate fixed on the fire-box and carrying vertical trunnion-bearings, a motor-cylinder having trunnions fitted in said bearings, a piston and rod in said cylinder, a connection coupling the piston-rod to the upper arm of the shaker-shaft, a distribution-valve controlling the supply and exhaust of motive fluid to and from the motor-cylinder, an operating-lever connected to the distribution-valve, and a rod or link coupling the lower arm of the shaker-shaft to a rocking grate.

3. In a grate-shaking appliance, the combination of a shaker-shaft journaled vertically in bearings on the back head of a fire-box, upper and lower arms fixed on said shaft, a motor-cylinder fixed on the fire-box, a piston and rod in said cylinder, means to

couple the piston-rod to the upper arm of the shaker-shaft, a distribution-valve controlling the supply and exhaust of motive fluid to and from the motor-cylinder, an operating-lever 5 connected to the distribution-valve, a rod or link coupling the lower arm of the shaker-shaft to a rocking grate, and an arm fixed on the shaker-shaft and adapted for connection to a hand-operating lever.

10 4. In a grate-shaking appliance, the combination of a revoluble shaker-shaft journaled in bearings on the fire-box, one of said bearings being provided with a socket, upper and lower arms on said shaft, a fluid-pressure- 15 motor cylinder supported on the fire-box, a piston in said cylinder coupled to the upper arm of the shaker-shaft, a link for connecting the lower arm of the shaft to a plurality of rocking grate-bars, a short intermediate arm 20 fixed on said shaft, a stub coupled to said arm and adapted to engage the socket in said bearing and a hand-lever when not engaging said socket.

25 5. In a grate-shaking appliance, the combination of a revoluble shaker-shaft journaled in bearings on a fire-box, one of said bearings being provided with a socket, upper and lower arms on said shaft, a fluid-pres-

sure-motor cylinder supported on the fire-box, a piston in said cylinder adapted to be 30 coupled to the upper arm of the shaker-shaft, a link for connecting the lower arm of the shaft to a plurality of rocking grate-bars, a short intermediate arm fixed on said shaft, a 35 stub coupled to said arm and adapted to engage the socket in said bearing, a stirrup on the shaft and adapted to receive said stub when not engaged in said bearing.

6. In a grate-shaking appliance, the combination with a fire-box of a boiler, of a shaker-shaft journaled thereto, a fire-door in said box, the upper end of said shaker-shaft extending above said fire-door, a fluid-pressure motor connected to said fire-box above the fire-door, means to couple said motor to said 40 shaft to rock the latter, a plurality of rocking grate-bars, means to couple said bars to said shaft, means to lock said shaft, when not in operation, in position to hold said grate-bars horizontal, and means to shake said shaker-shaft by hand in the event of the failure of 45 said motor.

WILLIAM H. HUGHES.
